UNITED STATES PATENT OFFICE

ARTHUR W. COLE, OF KALAMAZOO, MICHIGAN, ASSIGNOR TO REX PAPER COMPANY,
OF KALAMAZOO, MICHIGAN

SUPPORT FOR PAPER ROLLS AND THE LIKE

Application filed July 30, 1928. Serial No. 296,268.

Rolls of paper as they come from roll paper making machines are of considerable width and diameter and very heavy. The paper of these rolls is frequently cut into 5 sheets and strips and for satisfactory results it is necessary that the roll be accurately aligned or adjusted in relation to the cutting or slitting machine.

The main objects of this invention are to 10 provide a support for paper rolls and the like which facilitates the handling of the same, minimizes labor and enables very accurate adjustment or aligning.

Objects relating to details and economies 15 of construction and operation of my invention will appear from the description to follow. The invention is defined and pointed out in the claims.

A structure which is a preferred embodiment of my invention is illustrated in the accompanying drawing, in which:

Fig. 1 is a perspective view of my improved support, a roll of paper being indicated in position thereon by dotted lines.

Fig. 2 is a fragmentary view partially in vertical section on line 2—2 of Fig. 1, rolls of paper being indicated thereon by dotted lines.

In the drawing similar reference characters refer to similar parts throughout the several views.

Referring to the drawing, the embodiment illustrated comprises a pair of horizontal spaced bed members 1 and 2 supported by pedestals 3 adjacent the ends thereof. These bed members and the pedestals are, in the embodiment illustrated, integral castings and adapted to support a load. The bed members have horizontal groove-like ways 4 at their ends.

Roll supporting bars 5 and 6 are slidably mounted in these ways and are provided with stops 7 adjacent one end thereof and are adapted to support the spindle 8 of a 45 roll of paper indicated by dotted lines at 9.

The bed member 2 has a longitudinal slot 10 therein opening to the bottom of its way 4 to receive and permit reciprocating movement of the depending arm 11 secured to 50 the supporting bar 6.

An adjusting shaft 12 is rotatably mounted in a bore-like bearing 13 provided therefor in one of the pedestals 3 and has threaded engagement with the arm 11 so that by rotation of the shaft, the supporting bar 6 is adjusted in its way. A hand wheel 14 is provided for the shaft 12.

With the parts thus arranged, a roll of paper provided with a supporting spindle may be rolled upon the supporting bars and rolled along thereon into engagement with the stop 7. A web of paper indicated at 15 is then adjusted in proper relation to the cutting or slitting machine and the supporting bar 6 may be adjusted to accurately align the web of paper or to position it so that the web of paper is delivered to the cutting machine in the proper relation.

In Fig. 2, a second roll of paper, as 16, is shown in position on the supporting members to be advanced to a delivery position when the roll 9 is exhausted.

The pedestals are of such height that the structure may be delivered from a truck with the supporting spindles in proper position to engage the supporting bars.

I have illustrated and described my improvements in an embodiment which I have found very satisfactory. I have not attempted to illustrate or describe certain modifications or adaptations as I believe this disclosure will enable those skilled in the art to embody or adapt my improvements as may be desired.

Having thus described my invention, what I claim as new and desire to secure by Letters Patent, is:

1. A support for paper rolls and the like comprising spaced horizontal bed members provided with supporting pedestals at the ends thereof and having groove-like ways in the faces thereof, one of said bed members being longitudinally slotted, roll supporting bars slidable in said ways and provided with stops, a downwardly projecting arm on one of said supporting bars disposed through said slot in said bed member, an adjusting shaft rotatably mounted on one of the pedestals and having threaded en-

gagement with said arm, and a hand wheel on said shaft.

2. A support for paper rolls and the like comprising spaced horizontal bed members having ways in the faces thereof, one of said bed members being longitudinally slotted, roll supporting bars slidable in said ways and provided with stops, a downwardly projecting arm on one of said supporting bars disposed through said slot in said bed member and an adjusting shaft having threaded engagement with said arm.

In witness whereof I have hereunto set my hand.

ARTHUR W. COLE.
